UNITED STATES PATENT OFFICE.

CHARLES H. COLLINS, OF WEST ALBANY, NEW YORK, ASSIGNOR TO S. SANFORD & SONS, INC., OF AMSTERDAM, NEW YORK.

LOOM FOR WEAVING AXMINSTER CARPETS AND RUGS.

1,400,941.

Specification of Letters Patent. Patented Dec. 20, 1921.

Application filed February 15, 1921. Serial No. 445,060.

To all whom it may concern:

Be it known that I, CHARLES H. COLLINS, a citizen of the United States of America, residing at West Albany, in the county of Albany and State of New York, have invented certain new and useful Improvements in Looms for Weaving Axminster Carpets and Rugs, of which the following is a specification.

10 My invention relates to looms for weaving Axminster carpets and rugs.

In the manufacture of Axminster carpets and rugs which are woven on the present type of looms, the yarns are dyed in the skein and afterward wound on spools or bobbins each of which contains, when full, approximately four hundred yards of yarn. These spools or bobbins are then placed on the spindles of a spool bank or frame (usu- 20 ally 252 on a bank—for a 36 inch fabric) preparatory to having a portion of each of the yarns from the various spools wound onto a thirty-six inch length, small diameter loom spool. About seven yards of each of

25 the 252 yarns are contained on a filled loom spool, and the winding is usually done by a setting frame such as the device for which United States Patent No. 1,185,633 was granted to me under date of June 6th, 1916.

30 After the loom spools have been filled, they are conveyed to the loom and placed on a pair of endless "spool chains" carried on suitable sprockets. In ordinary practice a machine making a twelve foot rug design requires chains carrying 504 of such spools—each spool being inserted twice in each rug once on each side of the center thereof. Such a loom, on account of the long spool chains required, occupies a great amount of val- 35 able factory space.

It is obvious that when plain or plain striped rugs or carpets are to be produced the spools could be inserted oftener and a fewer number of spools would suffice. This 45 however is impractical with the present looms as it would require a great part of the operator's time to keep fresh spools in-

serted—the capacity of the permissible size of spools which the looms are designed to handle being so small that frequent replacement would be necessary. It would also cause extra care on the part of the loom fixer as it is necessary to adjust the waste cam as often as there is material change in the diameter of the yarn on the loom spools in order to insure an evenly surfaced product without cutting an excessive amount of waste.

The object of my present invention is to provide a loom which may be adapted to weave either plain or striped Axminster carpets or rugs or Axminster rugs having a plain center and a plain border; which will occupy reduced factory space; which will reduce to a minimum the amount of waste which will be cut; and which will produce a smooth evenly surfaced carpet or rug and at less expense than the present looms, together with such other objects as may be hereafter set forth.

In designing my improved combination loom, I have planned to utilize as much of the present type of loom as possible in order that such looms may be "changed over" to my improved combination loom at comparatively small expense. With this in view my invention consists primarily of improved yarn feeding and inserting mechanisms applied to the usual Axminster loom; and of substituting a spool rack of any suitable type adapted to carry the usual spools or bobbins of yarn, in place of the loom spools, endless spool carrying chains, and spool inserting mechanism.

The improved mechanisms which I use, the different combinations of which my loom is capable and the different products which such combinations will produce, are illustrated by the accompanying drawings in which:

Figure 1. is a diagram of the yarn feeding and inserting mechanism, the loom adapted to make plain or plain striped Axminster carpets.

Fig. 2. is a side elevation of a portion of a loom arranged as in Fig. 1, and illustrates the yarn feeding mechanism.

Fig. 3. is a partial front elevation of my combination loom arranged as above.

Fig. 4. is a side elevation of the traveling tube frame group.

Fig. 5. is a front elevation of a portion of the same.

Fig. 6. is a detail of the gravity yarn tension bar.

Fig. 7. is a diagram of the secondary yarn feeding mechanism and the inserting mechanism.

Fig. 8. is a side elevation of the preferred form of traveling tube frame group structure.

Fig. 9. is a front elevation of a portion of the same.

Fig. 10. is a partial end elevation of one type of spool bank or rack.

Figs. 11 and 12 illustrate the carpet patterns which the loom is adapted to weave when arranged as per Figs. 1, 2 and 3.

Fig. 13. is a diagram of the yarn feeding and inserting mechanisms when the full combination is used.

Fig. 14. illustrates an arrangement of ratchets on the bell crank lever operating the feeding mechanism, which makes it possible to easily and quickly change from the primary to the secondary feed or vice versa.

Fig. 15. illustrates the type of rug which the full combination will produce.

The same reference characters refer to the same parts throughout the several views.

I will first explain my positive yarn feeding mechanism which is shown in diagram in Fig. 1 and which consists of a series of feed rolls, 4, 5, 6 and 7, geared together in pairs and driven from the "chain cam" shaft of the loom.

On the chain cam shaft 8 is fastened a cam 9 against which the cam follower 10 on the lever 11 is adapted to ride. The lever 11 is pivoted at 15 to the frame 43 of the loom or other suitable support. A bell crank lever 12, pivoted on the loom frame or other suitable support, has adjustably mounted in one arm thereof a bearing block 13, connected by a rod 14, to the free end of the lever 11. To the other arm of the lever 12, is pivotally attached a ratchet 16, adapted to engage with and drive the ratchet wheel 18 fastened on the shaft of the feed roll 4. The shafts of the feed rolls 4 and 6 are provided with sprocket wheels between which a chain 19 forms an operative connection.

A reed 20 is preferably provided to keep the yarns in proper alignment, and an idle roll 21 may be provided to change the direction of the yarns so as to cause increased frictional grip between the yarns and the roll 4 by causing the yarns to lie in contact

with a greater portion of the circumference 65 of said roll.

Arranged in the manner shown and described and the yarns threaded through the rolls as illustrated, each time the chain cam shaft 8, revolves, the high point on the cam 9 will force upward the cam follower 10, on the lever 11 and the end of the lever working through the rod 14 will force upward the arm of the bell crank lever 12 to which the rod is connected and will cause the ratchet 16 to be advanced enough to engage the next tooth of the ratchet wheel 18.

As the high point on the cam 9 passes from under the cam follower 10, the weight of the rod 9 and lever 11, which may be assisted by the spring 22, or other suitable means, will cause a reverse action, and the ratchet 16, will cause a partial rotation of the ratchet wheel, and of all the feed rolls, and deliver a fixed predetermined amount 80 of yarn with each revolution of the chain cam shaft 8.

A method of transmitting power from the chain cam shaft to the feed rolls is illustrated in Fig. 2.

In Fig. 7, I illustrate a modification of the feeding mechanism which I prefer to use as the secondary yarn feed when it is desired to produce Axminster rugs which are to have a body or one solid color and a border 95 of another solid color. In this device, I use a large spool or beam 24 in place of the rolls 6, and 7, and omit the operative connection 19, between the first and second pair of rolls. On the yarn beam 24 are wound the yarns 100 25 which are to make the cross or end border of the rug.

I will next describe the inserting mechanism or traveling tube frame group, which I use when it is desired to rebuild a present 105 loom for the production of plain or plain striped carpets only, and to utilize as many as possible of the parts of the original loom.

The mechanism is illustrated by Figs. 2, 3, 4 and 5 in which 26, represents the usual spool clutch which has been modified by forming therein bearings adapted to support one end of the rolls 29 and 30; and by adding thereto a bracket 31, adapted to have fastened thereto one end of the reed bar 32.

In making these changes in the loom, it is of course necessary to disconnect or remove the clutch opening mechanism.

The clutches having been modified, the idle roll 29, and the tension roll 30, are put in place after which the tube bar 33, carrying the yarn tubes 34, and the reed bar 32, are fastened to the clutches in any suitable manner.

The tension roll 30, is preferably rubber-covered, or roughened in some suitable manner so as to increase the frictional grip between the tension roll and the yarns in con-

tact therewith. (See diagrams, Figs. 1 and 7.)

When building a new loom, or when a present loom is to be rebuilt to a full combination, I prefer to use a special clutch member 36, adapted to grip a tube frame unit comprising a tube bar and yarn tubes 33, 34, reed bar 32, and rolls 29 and 30—all mounted on or in end pieces 37, so as to form 10 a unit adapted to be gripped by the clutches and which may be handled without liability to dis-arrangement of parts (see Figs. 8 and 9). The tube frame group (or inserting mechanism) constructed in this manner it 15 is a simple matter to remove the tube frame group handling the yarns from the spool bank which are to form the main portion of the rug and which I term the primary tube frame group, and to insert a tube frame 20 group handling the yarns from the yarn beam which are to form the "cross" or end borders of the rug and which I term the secondary tube frame group, or vice versa.

In order to facilitate work on the tube 25 frame while it is in the clutches, as for instance the hooking of yarns through the yarn tubes, I provide means whereby the tube frame and clutches may be raised to, and supported at, a point above the normal 30 "high" operating position of the tube frame.

These means consist of a shaft 39 mounted on the loom frame 43 at a point some distance above the operating positions of the tube frame; a ratchet wheel 40 fastened 35 on one end of the shaft; a pawl 41 mounted on the loom frame and in engagement with said ratchet wheel; and cables 38, 38, one end of each of which are fastened to the shaft so that the turning of the shaft will 40 cause the cables to be wound upon, or unwound from, said shaft; the other end of the cables are fastened to the pins 35 in the clutches 26, or to any other suitable point on the tube frame group. Thus arranged 45 the winding of the cables upon, or the unwinding from, the shaft will raise, or lower, the tube frame group and clutches, and the pawl provides means for holding them in the raised position.

50 The gravity tension bar 44, loosely mounted in suitable supporting guides 45, 45, keeps a substantially constant tension on the yarns between the delivery end of the yarn feeding mechanism and the tension rolls 29 and 30 regardless of the movement 55 or travel of the tube frame group or inserting mechanism.

A type of spool bank which may be used 60 with my improved combination loom is illustrated by Fig. 10, in which 46, represents a standard, 47, cross pieces bearing pins 48, on which spools 49 (on which the yarns are wound) fit loosely.

65 Referring to Fig. 13, it will be noted that in a full combination loom, two sets of yarn

feeding mechanisms are used. The "primary" being the same as illustrated in diagram by Fig. 1, and the secondary being the same as illustrated by Fig. 7.

In the full combination loom (see Fig. 70 13) when the end border 52, of a rug is to be woven the primary tube frame group is removed from the clutches and hung on the shaft 39, or on any other suitable support by means of hooks, 50, or any other suitable 75 means, and the secondary tube frame group inserted in the clutches.

When the end border of the rug has been woven, the secondary tube frame group is removed and hung from a suitable support 80 51, as indicated by dotted lines, (see Fig. 13) and the primary tube frame group reinserted in the clutches.

As rugs are woven in a string, it is only necessary to make a change in the tube 85 frames once for each rug—except the first and last rugs of the string.

An Axminster loom in which is embodied my improved yarn feeding mechanisms, 90 yarn inserting mechanisms, and gravity tension bar (and which is provided with suitable means for holding the necessary spools of yarn) may be adapted to make either plain or striped Axminster carpets or rugs, or Axminster rugs having a center of one 95 solid color and a border of another solid color; the loom and necessary spool bank will occupy a much smaller amount of factory space than the present type of Axminster loom; the definite yarn feed in conjunction with the rolling friction provided in 100 my tube frame group which holds the yarn ends in proper position and prevents their being jerked out of position by the movements of the tube frame group or inserting 105 mechanism, and also insures a substantially constant and even tension on the yarns when they are stretched preparatory to being cut by the shear mechanism of the loom, and results in a smooth even surfaced fabric being produced with a minimum of waste having 110 been cut.

In my improved loom there is of course no removing of loom spools from the spool chain and replacing of same on the chain, 115 so I am able to reduce the necessary motion of the clutches and to work with the tube frame group nearer to the fabric. This permits of easier or smoother movements of the inserting mechanism.

120 It will be seen that by the use of my improved loom, I am enabled to eliminate the somewhat costly operation of winding the yarns from the spools or bobbins onto the loom spools, and to eliminate the cost of 125 such spools and the upkeep of the spools and of the tube bars and yarn tubes which of necessity form a part thereof. This effects a great saving in labor and upkeep as well as reducing the necessary investment 130

by the reduction in factory space required by the loom and necessary appurtenances; all of which contribute to the lowering of production costs.

5 I claim—

1. In a loom for weaving Axminster carpets and rugs, the combination with the usual weaving mechanism, of a positive tuft yarn feeding device driven therefrom and adapted to feed a fixed predetermined amount of tuft yarn during each cycle of the weaving mechanism, said device comprising two pairs of coating rolls joined by an operative connection; and reeds, one mounted 10 in the rear of each of said pairs.

2. In a loom for weaving Axminster carpets and rugs, the combination with the usual weaving mechanism of a tuft yarn feeding mechanism adapted to feed a fixed 20 predetermined amount of tuft yarns at the proper time in each cycle of the loom; a tube frame normally in constant position between the spool clutches of the loom, and having formed thereon means for applying friction 25 to the tuft yarns before they enter the yarn tubes of said frame; and means for applying tension to the tuft yarns between the delivery point of the feeding mechanism and the point at which said friction means operate.

3. In a loom for weaving Axminster carpets and rugs, the combination with the usual weaving mechanism of a tuft yarn feeding mechanism adapted to feed a fixed 35 predetermined amount of tuft yarns at the proper time in each cycle of the loom; a tube frame normally in constant position between the spool clutches of the loom, and having formed thereon means for applying friction 40 to the tuft yarns before they enter the yarn tubes of said frame; and a rod lying on the tuft yarns so as to apply tension thereto at a point between the delivery point of the feeding mechanism and the point at which said friction means operate.

4. In a loom for weaving Axminster carpets and rugs, the combination with the usual weaving and spool holding mechanism, of a tube frame unit comprising end 50 pieces adapted to be gripped by the usual spool clutches of the loom, and having fastened thereto a tube bar with yarn tubes, and a reed bar, and having mounted therein a pair of coating rollers adapted to be rotated 55 by the friction of the tuft yarns as they are drawn between said rollers.

5. In a loom for weaving Axminster carpets and rugs, the combination with the usual weaving and spool holding mechanism, of a tube frame normally in constant 60 position between the spool clutches of the loom and provided with means for applying friction to the tuft yarns at a point adjacent that at which they enter the yarn tubes of 65 said tube frame.

6. In a loom for weaving Axminster carpets and rugs, the combination with the usual weaving mechanism of a traveling tube frame unit comprising a tube frame and yarn tubes, a reed bar, and a pair of rollers 70 adapted to apply rolling friction to the tuft yarns at a point adjacent that at which they enter the yarn tubes; means for feeding a fixed predetermined amount of each of said 75 yarns during each cycle of the loom; and means for applying a substantially constant tension to said yarns at a point between the delivery point of the feeding mechanism and the point at which said rolling friction is applied.

7. In a loom for weaving Axminster carpets and rugs, the combination with the usual weaving mechanism of means for feeding a fixed predetermined amount of each of the tuft yarns being woven into the fabric 85 with each cycle of the loom; rolling friction applied to said yarns at a point adjacent that at which they enter the yarn tubes of the inserting mechanism; and a gravity tension bar applying tension to said yarns at a point between the delivery point of the feeding mechanism and the point at which said 90 rolling friction is applied.

8. In a loom for weaving Axminster carpets and rugs, the combination with the 95 usual weaving mechanism of a tuft yarn feeding mechanism adapted to draw the yarns from spools and deliver a fixed predetermined amount of each yarn toward the tube frame; spool clutches; a tube frame normally in constant position between said spool 100 clutches, and means connected therewith for applying rolling friction to the tuft yarns; and means for applying substantially constant tension to the tuft yarns between the 105 delivery point of the feeding mechanism and the point at which rolling friction is applied.

9. In a loom for weaving Axminster carpets and rugs, the combination with the 110 usual weaving mechanism, of a pair of coating feed rolls adapted to draw the tuft yarns from a beam and deliver a fixed predetermined amount of each yarn toward the tube frame; spool clutches; a tube frame normally in constant position between said spool 115 clutches and having means connected therewith for applying rolling friction to the tuft yarns; and means for applying substantially constant tension to the tuft yarns 120 between the feed rolls and the point at which rolling friction is applied.

10. In a loom for weaving Axminster carpets and rugs, the combination with the usual weaving and spool holding mechanism, of a primary tuft yarn feeding mechanism adapted to draw yarns from spools and bobbins, and a secondary tuft yarn feeding mechanism adapted to draw yarns from a beam, both of said feeding mechanisms 125 130

adapted to feed a fixed predetermined amount of tuft yarn with each cycle of the weaving mechanism; means for operatively connecting either of said feeding mechanisms, at will, to a moving part of said weaving mechanism; a tube frame support; a pair of tube frames, one adapted to handle the tuft yarns from the primary yarn feed, the other to handle the tuft yarns from the 10 secondary yarn feed, said tube frames and yarn feeds so arranged that either tube frame may be inserted between the spool clutches of the loom, and it and the feeding mechanism supplying yarn thereto, operated while the other is hung from said tube frame 15 support, without interfering with the other tube frame and feeding mechanism.

In testimony whereof I have affixed my signature.

CHARLES H. COLLINS.
